US00D695469S

(12) **United States Design Patent**
Dougherty et al.

(10) **Patent No.:** **US D695,469 S**
(b4) **Date of Patent:** **** Dec. 10, 2013**

(54) **ADJUSTABLE DOG COLLAR**

(76) Inventors: **Jacqueline Dougherty**, Jacksonville, FL (US); **Edith Cooper**, Jacksonville, FL (US)

(**) Term: **14 Years**

(21) Appl. No.: **29/415,892**

(22) Filed: **Mar. 15, 2012**

(51) LOC (9) Cl. **30-04**

(52) U.S. Cl.

USPC **D30/153**; D30/152

(58) **Field of Classification Search**

USPC ..... 318/257; D30/154, 160, 151, 199, 153, D30/152; 119/707-712, 786-788, 791, 780, 119/782, 769-771, 792-799, 758, 760, 784, 119/802, 856, 857, 863, 865, 719, 859, 908, 119/776; D21/791, 840; D8/1, 14, 47; 248/121, 521, 545, 499, 145, 156, 508, 248/530, 125.1, 125.3, 125.8, 690; 211/205; 52/155, 166, 157, 162, 163; 135/118; 403/360, 378; 473/149, 147; D26/138; 362/401; 410/101; 405/259.1, 244; 182/3; 24/523, 525, 24/299, 594.11, DIG. 35, 3.2, 600.7, 905; D24/199; 54/71, 34; 267/113, 136, 34, 267/70-72; 16/66; 340/573.3, 668; 294/82.34, 19.1; 114/221 R; 441/75; 128/878, 882, DIG. 15; D29/120.1-120.2, 100, 101.1; D2/627, D2/624, 631

(57) **CLAIM**

The ornamental design for adjustable dog collar, as shown and described.

DESCRIPTION

FIG. 1 is a front elevational view of an adjustable dog collar showing my new design;

FIG. 2 is a side elevational view thereof;

FIG. 3 is a top elevational view thereof;

FIG. 4 is a bottom elevational view thereof;

FIG. 5 is an isometric elevational view thereof; and,

FIG. 6 is an in use view of the device.

The broken line showing of a dog illustrates environmental use, and is not claimed.

1 Claim, 4 Drawing Sheets
